UNITED STATES PATENT OFFICE.

ISAAC PATRICK, OF NEW YORK, N. Y., ASSIGNOR TO E. W. BLISS COMPANY, OF BROOKLYN, NEW YORK, A CORPORATION OF WEST VIRGINIA.

MACHINE FOR PUNCHING OR SWAGING RIMS OR THE LIKE.

Application filed July 2, 1924. Serial No. 723,727.

To all whom it may concern:

Be it known that I, ISAAC PATRICK, a citizen of the United States of America, residing in the borough of Queens, city and State of New York, have invented certain new and useful Improvements in Machines for Punching or Swaging Rims or the like, of which the following is a specification.

This invention relates to machines for 10 perforating, embossing, or otherwise punching or swaging annular bands such as metal rims, tires, or other similar objects. The punching operation is performed in radial directions with respect to the axis of the annulus. The machine is especially adapted 15 for the simultaneous formation of multiple punchings equally spaced angularly so as to form the punchings with equal circumferential spacing. The machine to be described is especially adapted for the punching 20 of metal rims or felloes for motor car wheels, although adapted to other analogous uses.

The invention provides a machine including 25 a means for holding or properly gauging or centering the rim to be punched, and a series of punching means preferably equal in number to the punchings to be made, and arranged radially in a plane coinciding with 30 the plane of the axes of the punchings (assuming the latter to be arranged in a single plane), and with operating mechanism whereby the punches are driven simultaneously, so that they act alike and equally 35 upon the rim at the stated distance or angular intervals required by the locations in which the punchings are to be formed. The 40 punching means comprise each two coacting punches which are reciprocally adapted for performing the type of punching required, as in the case of spoke punchings for wheel 45 rims, a hole with a necked up margin; these punches act from the outer and inner sides of the rim and reciprocally adapt themselves thereto by both being made movable in a radial direction, so that as they come together on opposite sides of the stock they assume radial positions in accord with the radii of the circles describing the inner and 50 outer surfaces of the stock, and in being forced together each reacts against the other so that they indent and emboss the stock of which the rim is made, without otherwise affecting or distorting the rim. Means are 55 provided for guiding or gauging the rim

when placed in position, and for holding it fast during the punching operation.

The general nature of the invention being thus indicated, I will proceed to describe in detail the preferred embodiment thereof 60 with reference to the accompanying drawings which illustrate a machine for punching and necking up the spoke holes, twelve in number and equidistantly spaced, in a rim for an automobile wheel, the particular 65 rim being of the section shown in Fig. 7. In these drawings,—

Figure 1 is an oblique elevation looking in the direction of the arrow 1 in Fig. 2;

Fig. 2 is a transverse section on the line 70 2—2 in Fig. 1;

Fig. 3 is a section in a plane transverse to Fig. 2, as indicated by the line 3—3, the view being drawn to half the scale of the preceding figures; 75

Fig. 4 is a radial section through any one of the punching means, as indicated, for example, by the line 4—4 in Fig. 1, the view being drawn to a larger scale and showing the punches before operating; 80

Fig. 5 is a fragmentary section in the same radial plane as Fig. 4, being on a larger scale and showing the punches just after operating;

Fig. 6 is a transverse section on the line 85 6—6 in Fig. 4;

Fig. 7 is a fragmentary section showing the rim-holding means in the plane of the line 7—7 in Fig. 1, the view being to the same scale as Fig. 5; 90

Fig. 8 is a fragmentary plan of Fig. 7, the rim being in section on the line 8—8 therein;

Fig. 9 is a fragmentary view corresponding to Fig. 7, but showing an adaptation to 95 a smaller size of rim.

Referring to the drawings, the machine is supported on any suitable frame A to which is attached a table B which is preferably arranged at an inclination, as shown in Fig. 100 2, to facilitate applying and removing the rims. A rim undergoing operation is shown at C. It is seated against a bearing ring D and centered thereon by any suitable guiding or centering means such as a circular 105 series of projecting lugs d (Fig. 7) projecting from or attached to the ring D, or any other suitable centering means. Any suitable number of radial punching means are arranged at such prescribed intervals as 110

are required for the punching of the various holes in the rim. These punching means may include each a primary punch E and a secondary punch F, the relation of which best appears from Figs. 4 and 5. The punches F are (in this instance) arranged inside the rim, and the punches E outside the same. The punches are mounted to move in a radial direction toward and from each other. When the rim is first applied, they are separated as shown in Fig. 4; afterward they approach each other until they reach the position shown in Fig. 5. The precise shape and contour of the working ends of the punches will depend upon the nature of the punching or swaging operation to be accomplished. A suitable form is that shown in Fig. 5, where the primary punch E has at its center a projection e which acts against the end of the punch F to punch out a hole in the metal, the punching scrap entering a bore f in the latter. With the construction shown, the working end of the punch F then acts as a secondary male punch to swage up and expand the original portion of the metal or stock around the perforation and turn it up into a hollow e' in the punch E, this constituting a necking operation which leaves the metal out-turned and enlarged at the marginal portion of the perforation. Any other reciprocal construction of primary and secondary punches may, however, be substituted, according to the work desired to be done.

The punches E, F are suitably mounted on operating mechanism whereby they may be brought together from opposite sides to perform the punching operation. In the specific construction shown they are carried by slides movable radially and operated by mechanism such that each reacts upon the other, so that they may mutually adapt themselves to the radial position of the stock between them. This is best accomplished by mounting the punch F in a portion G' of a slide G, and mounting punch E on a secondary slide H. The portion G' projects up within the rim, and the slide H is correspondingly located exteriorly of the rim. The slide H may be superposed upon and guided by the slide G, but this is not essential. The slide G has at its outer end an upward projection G². Operating mechanism for reciprocally advancing and retracting the slides is conveniently applied to act between and against the slide H and projection G² so as to tend to propel them equally in opposite directions. This operating mechanism preferably comprises a toggle or knee joint composed of links J, J, pivoted to H and G² respectively, and united by a pin I which couples them to the upper end of a connecting bar or link K which extends down through the table B. The several link bars K K are connected, as by pins L,

to a slide M which is mounted on slideways m, m beneath the table so as to reciprocate in a direction perpendicular to the plane of the table. By such reciprocation the toggles are straightened from the buckled position shown in Fig. 4, to the position shown in Fig. 2. In this operation the punches of each pair are forced together, and if either one abuts the stock in advance of the other it is stopped thereby while the other punch, reacting against the first, is brought into contact with the stock, whereupon they penetrate it to form the punching in the manner already described.

Thus the two punches of each pair have what may be called a floating or dynamically balanced mounting, whereby either may move to some extent independently of the other, and the impelling means for each reacts against the other punch member, so that whichever one first encounters the stock thereby becomes the abutment against which the movement of the other punch is accomplished, until both are in engagement with the stock, whereupon they move mutually together in performing the punching operation already described. In carrying out this feature of the invention it is preferable to mount the punches upon slides, as described, in order that they may be given a true rectilinear movement, and to move them by operating means which will act upon each while reacting upon the other, for which purpose a toggle motion, as described, is a suitable and most convenient means, but the invention is not limited thereto.

The rim or other annular structure to be punched requires to be firmly held during the punching operation, and for this purpose may be clamped down to the ring D by any suitable means. A convenient construction is that shown, consisting of four (more or less) clamping hooks or dogs P, one of which is shown in Figs. 7 and 8, pivoted on a pin p and jointed to the upper end of a rod Q, the lower end of which is connected to some portion of the slide M (or any other convenient operating means), as by carrying it through a perforated bracket on the slide, and preferably by interposing a spring q held by adjustable nuts r. Thus, during the preliminary downward movement of the slide M, the clamping hooks P are swung inwardly from the position shown in dotted lines to that shown in full lines in Fig. 7, so that their hooked ends bear down upon the inturned flange e of the rim C with a strength depending upon the stress to which the spring q is compressed.

In the case of rims for motor car wheels which are to carry a demountable tire rim, it is common to punch holes through the flanges of the rim C in a direction parallel to the axis (vertically in Figs. 4 and 7), and as this is commonly done prior to the punch-

ing of the spoke holes for which the present machine is specifically designed, it is desirable to correctly space or alternate the respective punchings. This may be accomplished by providing the ring D with one or more gauging pins t suitably placed to receive the holes already punched for the fastening bolts of the detachable tire rim. One of these gauging pins t is shown in Figs. 7 10 and 8.

It is sometimes desirable at the end of the punching operation, after the dies have separated (Fig. 4), and to facilitate the lifting of the punched rim, to provide a knock-out 15 for partly removing or feeding off the rim. This may conveniently be accomplished by forming on each clamping hook P a projection u (Fig. 7) which on the upstroke of the rod Q will strike the lower flange of the 20 rim and lift it enough to free it partly from the centering projections d, so that it may be more readily lifted off by the operator. This operation is conveniently accomplished by utilizing the upward movement of the slide 25 M (to the position shown in dotted lines M' in Fig. 7), in which position it strikes an adjustable collar s on the rod Q, which forcibly lifts the rod and thus tilts the locking dogs P to the position shown in dotted lines, thus 30 first freeing and afterward displacing the punched rim.

The machine may be variously operated. In the construction shown a driving wheel R turns the shaft of a pinion R' which drives 35 a gear wheel S fixed on a crank-shaft T extended beneath the table, having suitable bearings in the frame A. This shaft has cranks T' engaged by pitman rods U, U which are coupled by pins V to the slide M 40 in order to reciprocate this slide bodily toward and from the table B. The movement of this slide from its upper position of rest to its lower position first applies the clamping dogs P to hold the rim fast, and then 45 straightens the toggles J for driving the punches, and then on the return stroke buckles the toggles and finally releases the clamping dogs and slightly lifts the rim. The machine should then stop while the operator 50 lifts out the punched rim and puts a new one in place for the next operation. This is accomplished by any ordinary one-revolution clutch, such as are well known as applied to punching presses, and which require 55 no illustration.

The punches E, F may be variously constructed and mounted. In Fig. 4 the punch E is shown as coupled by a union 10 to a shank 11 seated in the slide H and fastened 60 therein by a set-screw 12. For adjusting the projection of the punch a screw plug 13 is arranged behind the shank 11 so that it may be set up or back and then fastened by a set-screw 14. In similar manner the 65 punch F is formed with its integral shank

entered within a bore in the slide projection G' and set fast by a screw 15, its adjustment being accomplished by a backing screw 16 which is set after adjustment by the set-screw 17. The bore f through the shank of 70 the punch F is extended through the screw 16, so that the successive punching scraps formed in punching the initial perforations in the stock are forced back through these bores and eventually fall into a hopper 18 75 and are guided down a central outlet chute 19.

While the precise construction and guiding of the slides G, H, is unessential, the construction best shown in Fig. 6 is suitable. 80 The slide G is dovetailed into a slideway in the table B and projects partly above the table to form a dovetailed slideway embraced by the under portion of the slide H, an adjusting key 20 being interposed for 85 taking up lost motion.

The machine just described may be provided with any suitable adjustments. The range of motion between the punches E, F, when separated, is ample for adapting the 90 machine without other adjustment to several different sizes of rims. It is, however, desirable to provide for each size of rim a separate seating ring D with its appropriate clamping dogs P, P. As an example, there 95 is shown in Fig. 9 a provision for seating and clamping a smaller size rim C', the seating ring D being replaced by a ring D', and the clamping dog P being replaced by a similar dog P' having, however, a longer hook arm 100 or clamping nose reaching over far enough to engage a smaller diameter of the inturned flange of the rim. This figure shows no knock-out for assisting to release the 105 punched rim.

The machine described is shown as constructed for punching twelve equidistant spoke holes in a standard motor wheel rim or felloe, for which purpose the radial punches and punch slides are arranged at 110 equal angular intervals, as shown in Fig. 1. For punching annular objects requiring other angular arrangement or spacing of punches, the punches and slides will of course be correspondingly displaced. If desired, adjustable mountings may be provided for the slides, whereby they may be set around at different angular distances so as to adapt the machine for punching, for example, ten or fourteen holes instead of 115 twelve. While symmetrical or equidistant spacing of the holes is most usual, yet for punching some objects an unsymmetrical or irregular spacing may be required.

For the punching of motor wheel rims, 120 the machine here shown and described has certain important advantages. In the making of such rims it is customary to take a flat strip or band, bend it into hoop form, and weld its ends together; thereupon the hoop

is passed between rolls to roll up the opposite flanges for the rim; then to bring the rim into true circular form, it is put in an expanding or stretching machine, whereby it is slightly stretched enough to give a new set to the metal; it is then punched with a hole for the tire valve and holes for the rim bolts, and then the radial spoke holes are punched, commonly by a single punch or by 10 a machine having two diametrically-opposite punches, in either case the rim being set or indexed around annularly after each punching to bring it into place for the next punching; these methods of punching always bring 15 the last holes punched out of true spacing with the holes first punched, and great difficulty is experienced in avoiding that the variation in spacing shall exceed the limit of tolerance; finally, since the punching 20 operation somewhat distorts the rim out of a true circle, it requires to be again trued, and this is commonly accomplished by putting it in a machine which by exterior pressure contracts it to a smaller circumference 25 and at the same time gives the metal a set such that it will retain the true circular form to which it is forced. The machine of my invention simplifies these operations, since the spoke punchings are performed 30 simultaneously, and by symmetrical operations which avoid any distortion of the rim, and by means which accomplishes the minutely correct angular spacing of the punchings; and since no distortion results 35 from the punching operations, the final truing of the rim by a contracting operation is rendered needless.

Throughout the specification and appended claims the term "punches" has been 40 used to denote the two reciprocally male and female elements which coact to perform a desired operation on the rim, and it is immaterial as to which of the elements is the male and which the female, or whether each acts in both capacities, as is the case where various types of compound punches are used.

It will be further understood that while the machine shown and herein minutely described is a suitable, and thus far the preferred, embodiment of the invention, yet the invention is applicable to other constructions, and its mechanical features may be varied by the exercise of the judgment of a skilled mechanical designer, and within the scope of the appended claims. While I have throughout the description referred to the machine as for punching rims or analogous articles, yet in its particular embodiment here shown the machine both punches and 50 swages the rim at each punching point; and it is to be understood that either operation of punching or swaging, or both, are within the invention; and the term "punching" is to be understood as including not merely perforating, but also embossing or otherwise

swaging the work, it being immaterial to my invention whether the opposed punch elements mutually cut through the work or merely indent, emboss, or otherwise deform it, as may be desired.

I claim as my invention:—

1. In a machine for punching rims or the like, a plurality of radially-acting floating punches arranged radially around the rim, each comprising two opposed punch elements, and means for operating these punch elements in dynamic balance so that each reacts upon the other to punch the rim with equal stress on opposite sides.

2. In a machine for punching rims or the like, a plurality of radially-acting floating punches arranged radially around the rim, and means for operating them simultaneously to punch the rim.

3. In a machine for punching rims or the like, a plurality of radially-acting dynamically balanced punches arranged radially and symmetrically around the rim, and means for operating them to punch the rim.

4. In a machine for punching rims or the like, a plurality of radially-movable pairs of floating slides arranged radially around the rim, mating punches carried thereby, the two elements of each punch carried by the two slides of one pair, and operating means for moving the slides of each pair in dynamic balance so that each punch element reacts upon the other to punch the rim.

5. In a machine for punching rims or the like, a plurality of pairs of oppositely moving punch elements arranged radially around the rim, and means for oppositely operating them in dynamic balance so that each reacts upon the other to punch the rim.

6. In a machine for punching rims or the like, a plurality of reciprocally-acting punches arranged radially around the rim, the punches acting simultaneously from opposite sides of the stock and in operation each moving towards its reciprocal one to punch the rim.

7. In a machine for punching rims or the like, a plurality of pairs of punches arranged radially around the rim, the punches of each pair on opposite sides of the stock, and operating means for forcing them each toward the other to punch the stock between them, said operating means being adapted to substantially equalize the force oppositely applied on each punch against its mate.

8. In a rim punching machine, a pair of dynamically balanced punches, and operating means for forcing them together to punch the rim, such means acting in one direction against one punch and in the contrary direction against the other.

9. In a rim punching machine, a pair of

reciprocally-acting floating punches and operating means for forcing them together, the punches adapted to yield to adapt themselves to the position of the stock during the

5 actual punching operation.

10. In a rim punching machine, a pair of reciprocally-acting floating punches, slides carrying the punches, and operating means adapted to act in contrary directions and 10 with substantially equal force against the slides to bring the punches together.

11. In a rim punching machine, a pair of reciprocally-acting floating punches, slides carrying the punches, and operating mechanism 15 acting on the slides to force them in contrary directions, each slide, during the advancing movement of the punch, being free to move longitudinally independently of their mutually-advancing movement, 20 whereby the punches may adapt themselves to the position of the stock.

12. In a rim punching machine, a pair of reciprocally-acting punches, a slide having a portion projecting within the rim and 25 carrying one punch, another slide exterior to the rim carrying the other punch, and operating means for pressing the slides in contrary directions to bring the punches together, said means adapted to balance its 30 action upon each punch slide by the reaction against the other.

13. In a rim punching machine, a pair of reciprocally-acting floating punches, slides carrying the punches, and operating means 35 comprising a toggle with its links engaging the respective slides and an actuating connection to the knee joint of the toggle, the slides being substantially free to move longitudinally irrespective of the force of the 40 toggle.

14. In a machine for punching rims or the like, a plurality of pairs of punches arranged radially around the rim, and operating means for simultaneously forcing the 45 punches together, the punches of each pair free to move radially, whereby to adapt themselves to the location of the stock and thereupon to act upon the stock simultaneously.

50. 15. In a machine for punching rims or the like, a plurality of radially-acting punches, and operating mechanism therefor comprising a plurality of means for simultaneously forcing the respective punches together, and a reciprocating part engaging said plurality of means for moving them simultaneously.

55. 16. In a machine for punching rims or the like, a plurality of radially-acting floating punches arranged in co-acting pairs, and operating mechanism therefor comprising a plurality of means for simultaneously forc-

ing the punches of each pair together, a reciprocating slide, and operative connections between said slide and said plurality of means.

65

17. In a machine for punching rims or the like, a plurality of radially-acting pairs of floating punches, the outer punches adapted to enter the inner punches while perforating the stock, and the inner punches radially movable and made hollow to conduct the punching scrap toward the center, and means for receiving the scrap from the moving inner punches and discharging the scrap.

70

18. In a machine for punching rims or the like, a frame, a plurality of floating punches and their operating means, seating and gauging means for locating and holding the rim, said means being fixedly mounted on said frame.

80

19. In a machine for punching rims or the like, a plurality of punches with seating means for the rim and a plurality of clamping dogs movable to clamp the rim against said seating means in a direction perpendicular to the punch axes, and operating means for the punches and for said dogs movable to simultaneously actuate said dogs to clamp the rim in advance of the punching stroke.

85

20. The combination of claim 19, the clamping dogs having knock-out means operable on the unclamping stroke to displace the rim after punching.

90

21. In a machine for punching rims or the like, a plurality of punches and their operating means, with seating means for the rim and means for clamping the rim against said seating means, and a reciprocating slide engaging said clamping means for simultaneously operating them to clamp the rim.

95

22. In a machine for punching rims or the like, the combination of means for clamping the rim in place, punching means comprising radially-arranged punches for punching the rim, knock-out means and operating means adapted first to operate the clamping means to clamp the rim, then to operate the punching means to punch the rim, and finally to release the clamping means and knock out the rim, said cycle of events being effected by a single oscillation of said operating means.

100

23. In a machine for punching rims or the like, a plurality of punches and their operating means, and rim-clamping and rim-ejecting means comprising pivoted elements adapted to swing in one direction to clamp the rim in place, and in the other direction to lift the rim from its seat.

115

In witness whereof, I have hereunto signed my name.

120

ISAAC PATRICK.
